UNITED STATES PATENT OFFICE.

ROBERT REARDON, OF SAVANNAH, GEORGIA.

CAR-COUPING.

SPECIFICATION forming part of Letters Patent No. 774,533, dated November 8, 1904.

Application filed July 1, 1904. Serial No. 214,885. (No model.)

To all whom it may concern:

Be it known that I, ROBERT REARDON, a citizen of the United States, and a resident of Savannah, in the county of Chatham and State of Georgia, have invented a new and Improved Car-Coupler, of which the following is a full, clear, and exact description.

My invention relates to automatic double-knuckle car-couplers.

10 The objects of my invention are to provide for insuring the certainty of action of a car-coupler of the type mentioned, for providing an absolutely secure coupling, and for providing means for quickly and easily uncoupling the device by automatic action when the locking device is operated to unlock the knuckle.

With these and other objects in view my invention comprises certain mechanical devices, one embodiment of which will be illustrated 20 in the drawings and described in the specification and the scope of which will be defined in the appended claims.

Reference is to be had to the accompanying drawings, forming a part of this specification, 25 in which similar characters of reference indicate corresponding parts in all the figures.

Figure 1 is a plan view of one embodiment of my invention, showing two heads in locked position, one being partly in section to show 30 the interior construction. Fig. 2 is a sectional view of one of the heads, showing the parts in open position ready for engagement with the other head. Fig. 3 is a sectional view of one head, showing the parts in the position shown 35 in Fig. 1; and Fig. 4 is a perspective view of a detail hereinafter more particularly described.

This invention is an improvement upon my previous patent, No. 475,153, granted May 17, 1892, and certain parts of the apparatus shown 40 in said patent are for convenience illustrated here.

The heads *a* are substantially alike, but are formed right and left handed, so they may be fitted together in the manner indicated in Fig.

45 1. Each one is provided with a rear extension *a'*, having a pair of shoulders *a²* *a³* for attachment to the car. Knuckles *b* are pivoted to the heads at points *a⁴*. These knuckles may be of any desired construction, such as that 50 shown in my prior patent above referred to;

but they are preferably provided with two extensions *b'*, each one having a slot *b²* for the admission of the locking member. The knuckles are designed to normally assume the position shown in Fig. 2; but when acted upon by each other—that is, when one knuckle is 55 acted upon by the other—they are designed to assume the position shown in Fig. 1. The head is hollow for the purpose of receiving the knuckle, and when the device is in locked 60 position each knuckle will be swung on its pivot into the head.

The locking device *c* is pivoted to the upper part of the head by means of projections *c'*, which are preferably provided with perforations *c²*, by which the device is pivoted. The point at which it is pivoted is preferably located over the portion of the knuckle when the knuckle is in its innermost position. The locking device is provided with a shoulder *c³*, 70 adapted to form a rest on the top of the head, as shown in Fig. 3, and with a locking-tongue *c⁴*, adapted to enter the slot *b²*. An eye *c⁵* is also preferably provided for the attachment of a ring, chain, or any desired operating device. It will be seen that the locking device 75 passes through an opening *a⁵* in the head *a* and that the tongue extends down in a position almost under the pivotal point *c²*. It will be observed that on account of the shape of the locking device and the location of the point at which it is pivoted it will be adapted to be 80 acted upon by gravity in such a manner as to cause it to assume a position in which the shank will enter the slot *b²* in the knuckle without the application of any other force. 85

d is a member located within the head and pivoted thereto by means of a stud *d'*. It is provided with two extensions *d²* *d³*. When the parts are in the unlocked position, (shown in Fig. 2,) the part *d²* will be thrown backward so that the part *d³* projects into the path which will necessarily be traversed by the knuckle *b* when it is forced to swing inward on its pivot. It will be seen that upon swinging the 95 knuckle *b* in this direction and upon its coming in contact with the projection *d³* the member *d* will be swung on its pivot and the projection *d²* will act to force the tongue *c⁴* toward the knuckle. This, it is to be understood, is a 100

mere safeguard provided for the purpose of insuring the proper action of the locking device, which is expected to act by gravity without this aid. It will be understood, however, that upon the hard service of a railroad the parts may become clogged, and this positive action will absolutely insure the perfect working of the device. This pivoted member d also has another function: When the parts are in the position shown in Fig. 1, it will be forced to assume that position; but upon the unlocking of the device by raising the eye c^3 , as shown in Fig. 3 in dotted lines, the heel of the tongue c^4 will force the projection d^2 to the rear, and consequently swing the projection d^3 against the knuckle b and force it outwardly upon its pivot. This insures a positive operation of the knuckle upon its pivot and the forcing of it out of the head.

a^6 is a shelf or projection upon the interior of the head, located in contact with the locking-tongue c^4 , and, as is clearly illustrated in Fig. 1, serving to prevent motion of the latter out of the way of the knuckle. In other words, force exerted upon the knuckle to swing it outwardly upon its pivot will be expended in pressing the locking-tongue c^4 against this stationary projection a^6 , and will consequently have no effect upon the device and cannot by any possibility unlock the coupling. a^7 is a shelf or projection from the other side of the head adapted to support the knuckle.

It is thought from the above description the management and operation of the device will be obvious and that further description is unnecessary. It is to be understood, however, that the apparatus illustrated in the drawings and described herein is a mere illustration of a preferred form of my invention and that the latter is not limited to the details thereof, but that many modifications may be made therein within the scope of my invention. It will be obvious that many other forms of knuckles may be used with the other

devices mentioned, and I do not wish to be limited to the particular forms illustrated.

Having thus described my invention, I claim as new and desire to secure by Letters Patent—

1. In a car-coupler, the combination of a hollow head, a knuckle pivoted thereto and having a projection at one end provided with a horizontal slot, a locking member pivoted to the head at a point above a portion of the knuckle when swung into the head, said locking member having a tongue and a projection adapted to rest on the head and to hold the tongue in horizontal position and being adapted to be swung against the knuckle by gravity, and means for forcing the tongue into the slot when the knuckle is forced into the head. 60

2. In a car-coupler, the combination with a hollow head, a knuckle pivotally mounted thereon and adapted to be swung therein, said knuckle being provided with a projection at one end having a slot therein, automatic means 65 for locking said knuckle when swung into the head, said automatic means comprising a member pivoted to the head above a portion of the knuckle when the latter is swung into closed position, said member having a projection 70 adapted to hold the main part thereof in horizontal position and a locking-tongue adapted to enter the slot in said knuckle, and means for swinging said tongue in said slot and for swinging the knuckle outwardly upon its 75 pivot, comprising a pivoted member having two projections, one extending into the path of movement of said locking member and the other into the path of movement of said knuckle. 80

In testimony whereof I have signed my name to this specification in the presence of two subscribing witnesses.

ROBERT REARDON.
